TWO-WAY WALL LIGHT FIXTURE

Warren D. Anderson, 4041 Raleigh Ave.,
Minneapolis, Minn.

Filed May 22, 1958, Ser. No. 51,019

Term of patent 14 years

(Cl. D48—4)

Fig. 1

Fig. 2

Fig. 3

Fig. 4

Fig. 1 is a view in perspective of a two-way wall light fixture showing my new design;

Fig. 2 is a view in rear elevation, on a reduced scale, of the fixture of Fig. 1;

Fig. 3 is a view in bottom plan thereof; and

Fig. 4 is a view in end elevation thereof.

The end of the light fixture not shown is the same in appearance as the end shown.

I claim:

The ornamental design for a two-way wall light fixture, as shown and described.
